(57) **CLAIM**

The ornamental design for a tiki lantern arm, substantially as shown and described.

DESCRIPTION

FIG. 1 is a perspective view of the tiki lantern arm embodying my new design and shown attached to a rail.

FIG. 2 is a front view of the tiki lantern arm shown in FIG. 1.

FIG. 3 is a left side view of the tiki lantern arm shown in FIG. 1.

FIG. 4 is a rear view of the tiki lantern arm shown in FIG. 1.

FIG. 5 is a top view of the tiki lantern arm shown in FIG. 1; and,

FIG. 6 is a bottom view of the tiki lantern arm shown in FIG. 1.

The broken lines shown on the drawings are for illustrative purposes only and form no part of the claimed design.
